UNITED STATES PATENT OFFICE

162,100

EDUCATIONAL SPINNING TOP

Quan Wee, San Antonio, Tex.

Application April 8, 1949, Serial No. 1,868

Term of patent 14 years

(Cl. D34—5)

To all whom it may concern:

Be it known that I, Quan Wee, a citizen of China, residing at San Antonio, in the county of Bexar and State of Texas, have invented a new, original, and ornamental Design for an Educational Spinning Top, of which the following is a specification, reference being had to the accompanying drawing, forming part thereof.

Figure 1 is a perspective view of an educational spinning top, showing my new design,

Figure 2 is a top plan view thereof, and

Figure 3 is a cross-sectional view, taken substantially in the plane of the line 3—3 in Figure 1.

The dominant features of my new design as shown in solid lines in the drawing.

I claim:

The ornamental design for an educational spinning top, as shown and described.

QUAN WEE.
